S. N. HANKS

RAILWAY CROSSING GATE

Filed June 20, 1925

Inventor
S. N. Hanks,

Clarence O. Price
Attorney

UNITED STATES PATENT OFFICE.

SILVIA N. HANKS, OF OKOLONA, MISSISSIPPI.

RAILWAY-CROSSING GATE.

Application filed June 20, 1925. Serial No. 38,457.

The present invention relates to railway gate crossing structure, and more particularly to the operating mechanisms therefor.

The principal object of the invention is 5 to generally improve upon the structure shown in Letters Patent #1,503,444, issued to me on July 29th, 1924.

Another important object of the invention is to provide an improved mechanism 10 for swinging a gate downwardly or to a closed position, in relation to the crossing by the approach of a train in either direction, said means being operable only as the train approaches the crossing.

15 Another important object of the invention is to provide means for holding the gate in a closed position, and a mechanism for releasing said means.

A still further very important object of 20 the invention is to generally improve upon structures of this nature by the provision of an exceedingly simple mechanism, which is thoroughly reliable and efficient in operation, strong, durable, not likely to easily 25 become out of order, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

35 In the drawing:

Figure 1 is an elevation of my improved structure looking down the roadway across the tracks.

Figure 2 is a fragmentary top plan view 40 of the gate operating structure.

Figure 3 is a detail vertical section, taken substantially on the line 3-3 of Figure 2, looking in the direction of the arrows.

Figure 4 is another detail vertical section, 45 taken substantially on the line 4-4 of Figure 2, looking in the direction of the arrow.

Figure 5 is a similar section, showing the parts in a different position, and

Figure 6 is a top plan view, showing one 50 of the trips.

Referring to the drawing in detail, it will be seen that 1 designates a roadway crossed by the tracks 2. A post 3 is mounted in one corner formed by the intersection of the 55 roadway with the tracks and has pivoted on its upper end a gate bar 4. This gate bar 4

is pivoted intermediate its ends, one end being provided with a weight element 5 and said gate being provided adjacent the other end with a pivoted prop 6. A rod 7 is 60 slideable through the gate at a point between its pivot and weighted end 5. Springs 8 are disposed about the rod 7 one on each side of the gate bar 4. It will thus be seen that when the rod 7 is moved downwardly, the upper spring will be compressed and the gate bar 4 will be swung to an open position, and that when the rod 7 is moved upwardly, the lower spring 8 will be compressed and the gate bar moved to a horizontal or closed position, at which time the prop 6 will rest on the roadway 1. These structures allow sufficient latitude to the operating mechanism as will appear later in the description, so as to eliminate any sudden strains which might otherwise be placed thereon, such as would be occasioned by the limited movement of the gate bar 4 or by an obstacle being situated thereunder. These springs also prevent the gate bar from doing 70 injury to vehicles and person should they be caught under the same when it is being moved to a closed position.

A frame 9 is located alongside of one rail of the track 2 between said track and the post 3, and includes a pair of parallel members 10 and 11 extending longitudinally with the track 2 and a pair of transverse members 12 and 13 which extend from the ends of the member 11, so as to converge toward each other and merge into the ends of the member 10.

The frame 9 is located in a horizontal plane below the plane of the upper surfaces of the ties 14 and is attached to the ties as at 15, intermediate portions of the member 11 being bent upwardly for this purpose.

A shaft 16 is journaled as at 17 on the middle of the member 11 and through a plate 18 rising from the member 10. This shaft extends transversely of the track way and has a crank 19 on its end pivotally engaged with the bottom end of the rod 7.

If two gates 4 are used, one on each side of the track way, of course, the other end of the shaft 16 would be provided with a similar crank 19,

a duplication which it is unnecessary to illustrate in the drawings. A crank 20 is fixed intermediate its ends to the shaft 16, between the members 10 and 11 adjacent the latter, and has pulleys 21 journaled in its ends. Cables 22 are trained over the pul-

leys 21 and then extended back over themselves and fixed to the members 12 and 13, as is indicated at 23. It will thus be seen that by pulling either of the cables 22, the 5 crank 20 will be rocked in the same direction, and the other cable will be slackened. This rocking of the crank 20 will cause the 10 rocking of the shaft 16 and the crank 19, thereby actuating the gate to a closed position. A bar 25 is fixed intermediate its ends to the shaft 16 immediately above a longitudinally extending cross member 26, fixed to the intermediate portions of the members 12 and 13. A spring 27 is fixed to the upper 15 end of the bar 25 and to the member 26, and normally holds the bar 25 so that the shaft holds the crank 19 in such a position as to hold the gate normally raised with the assistance of its weighted end 5. A spring 20 catch 28 is fixed at one end as at 29, to the member 26, and has its free end engageable with a seat 30 formed on the lower end of the bar 25 so that when the gate is closed 25 and the bar is swung to tension the spring 27, the end of the catch 28 will engage in the seat 30, as is illustrated in Figure 4, for retaining the gate in its closed position. Adjacent the end of the spring catch 28 there is 30 formed a pump 32. A shaft 33 is journaled across the frame in plate 18 and in a plate 34 and terminates in a crank end 35, adjacent one track rail 2. A bowed spring 36 has one end fixed to one tie as at 37 and a pin and slot connection 38 with another tie so 35 that the flange of the wheel of a train will press downwardly on the spring 36 and tend to straighten the same out, in order that it will engage the crank end 35 and rock the shaft 33. A cross member 39 is mounted on 40 the shaft 33, adjacent the hump 32 and when the shaft is rocked as described, this cross member will depress the spring catch 28, releasing its ends from the seat 30, so that the spring 27 will be free to rock the bar 25 45 and the shaft 16 and allow the gate to open.

To both sides of the roadway 1, along the trackway 2, there is located a trip mechanism. These trip mechanisms are identical in construction, and operate to pull the cables 22 and a description in detail of one will suffice for both and for simplicity only one will be described in detail. The train engaging member 40 is disposed alongside of one rail 2, and at one end is provided 50 with an elongated slot 41, which receives a pin 42, rising from a tie 14. A link 43 is pivoted to the other end of the other member 40 and depends downwardly therefrom. The member 40 is constructed of spring 55 metal or the like, so that when a train approaches, as is indicated in dotted lines to the left of Figure 1, said member 40 will be bent so as to move the link 43 downwardly. This link 43 is pivotally engaged

with a bell crank lever 44. The link 45 is 65 pivoted to the bell crank lever 44 and also to a bell crank lever 46 pivoted on the rail 2, as at 47, and attached to the adjacent cable 22, so that when the member 40 is bent downwardly, as previously indicated, the bell 70 crank levers 44 and 47 are rocked to pull the cable 22 thereby rocking the crank 20, as previously indicated. When the train progresses past the cross road and comes into engagement with the other member 40, the 75 wheel will engage the link end thereof, so that the member 40 will be slid in the direction of the travel of the train, the link 43 swinging therewith and since the slotted end is free to move, the member 40 will move in 80 the direction of the travel of the train causing the swinging of link 43 on its pivotal connection with bell crank 44 until said member 40 is depressed sufficiently to disengage 85 with the train. The bell crank lever 40 will not be rocked sufficiently to cause any perceptible movement in the gate bar 4. After the train has passed by, a dash pot 49 is provided, and engages an extension 50 at the slotted end of the member 40 to return 90 it to its normal position slowly.

It is thought that the construction, operation, and advantages of the invention will now be clearly understood without a more detailed description thereof. It is apparent 95 that changes in the details of construction, and in the combination and arrangement of parts may be resorted to without departing from the spirit or scope of the invention as hereinafter claimed, or sacrificing any of its 100 advantages.

Having thus described my invention, what I claim as new is:

A crossing gate structure comprising a gate, a shaft, means operatively connecting the gate and the shaft so that the former may be operated by the latter, means for rocking the shaft, a bar fixed intermediate its ends to the shaft, a spring engaged with one end of the bar and pendent to normally hold the 105 shaft in such position as to dispose the gate open, a spring latch engageable with the other end of the bar for holding the shaft against rotation when the gate is closed, a second shaft having a cam engageable with the spring latch for releasing the same, a crank on the shaft last-mentioned, a bowed spring having one end fixed and the other end movably mounted, the intermediate portion of said bowed spring being disposed for 110 engaging the crank so that when said bowed spring is actuated by a car wheel the intermediate portion thereof engages the crank for turning the second shaft to cause the cam 115 for turning the second shaft to cause the cam to release the spring latch.

In testimony whereof I affix my signature.

SILVIA N. HANKS.
